UNITED STATES PATENT OFFICE.

NELS G. NELSON, OF ROCKFORD, ILLINOIS.

TOY SHOOTER.

1,191,530.

Specification of Letters Patent. Patented July 18, 1916.

Application filed March 31, 1916. Serial No. 87,892.

To all whom it may concern:

Be it known that I, NELS G. NELSON, a citizen of the United States, residing in the city of Rockford, county of Winnebago, and 5 State of Illinois, have invented certain new and useful Improvements in Toy Shooters, of which the following is a specification.

My invention relates to toy pistols and the like and its object is to provide a toy pistol 10 or shooter which cannot very well employ dangerous missiles or ammunition, the chief objection of parents and neighbors to the ordinary toy pistols.

Another object is to provide a form of 15 construction that is so simple and inexpensive that it may be sold for the few pennies comprising the average small boy's capital.

With these objects in view my invention consists in the novel construction of toy, 20 and its combination and arrangement of parts, all as hereinafter described in detail, illustrated in the accompanying drawing, and more particularly pointed out in the appended claims.

25 In the drawing Figure 1 is a side elevation of a shooter embodying my invention held in the hand and cocked. Fig. 2 is a similar view, but of the shooter alone and with the hammer and ball released. Fig. 3 is substantially a section taken on line 3—3 of Fig. 2. Fig. 4 is a section taken substantially on line 4—4 of Fig. 2. Fig. 5 is a perspective view of the hammer.

In the several views, 2 is the figure of the 35 fingers of a hand gripping the body—3—of the toy. This body is a flat plate of wood or metal the outlines of which are made to provide the grip portion, an approximately semicircular jaw opening 4, and a lug 5 to engage one end of a trigger tension spring 6 the other end of which is engaged by a lug 7 on a trigger 8 that is pivoted at 9 to one side of the body or plate 3. The ammunition or missile is a rubber, fiber, or other 40 comparatively soft ball 10 which may, if desired, be attached to a suitably lengthened string 11 the opposite end of which is tied to an eye or opening 12 in the grip portion of the plate 3. The jaw 4 takes the place of 45 the usual barrel and is adapted to hold only an elastic ball, such as a rubber ball which may be pressed into engagement between the two jaws—13 and 14, formed by the semi circular opening 4. Hence it cannot be loaded 50 with slugs, stones, or other of the usually hard missiles which cause broken windows and endanger the eyesight of playmates. The hammer is double, or bifurcated, straddles the plate 3 and is a flat plate of metal bent upon itself and formed to provide a 55 pair of pivot disks 15 and 16 of approximately circular form one of which has a cut away portion in its periphery producing a trigger notch or stop or shoulder 19 to be engaged by a tapered end 20 of the trigger 8. The upper part of the hammer has also a 60 pair of forwardly bulging striking portions 21 and 22 the sides of which afford convenient grip-holds between the user's thumb and forefinger when cocking the hammer. The 65 latter is mounted on a pivot 23 the ends of which engage holes 17 and 18 in the parts 15 and 16 and a similar opening 24 through the plate 3. The hammer is tensioned by a 70 spring 25 located in a slot 26 through the plate 3 and having one end attached to a hole or eye 27 in the body 3 and the other end attached to a cross-pin 28 having its ends anchored in holes 29 and 30 through the parts 15 and 16. The bend—31—in the 75 hammer may be projected above the jaw 13 to any desirable extent as a finger lug or hold, but since the cheek-line portions 21 and 22 afford, perhaps, the better grip the bend 31 will preferably be made close to the 80 upper edge of the body portion 3. The striking edges of the parts 21 and 22 may be broadened by suitable configuration of the 85 said parts if a greater surface area is desired to prevent their cutting the ball if the 90 metal plate forming the hammer is thin.

The above-described construction is very 95 light and thin, so the device may be conveniently carried as in a vest pocket, and it takes up no appreciable room wherever placed or packed. The solid rubber ball is well adapted for target practice and has the advantage, irrespective of a string attachment, that it will bounce back toward starting point and may be safely projected 100 against the walls of a room when weather conditions prevent outdoor play. The combination and arrangement of the parts are such that the hammer blow may be made quite powerful there being ample room for a strong spring 25 about which the palm of the hand or thumb and fingers naturally curve so as to make accidental pinching between the coils of the spring practically out of the question at the moment when the 105 110

trigger is pulled by reason of the fact that this act tends to curve the fingers outwardly and away from the spring.

Having thus described my invention, I claim as new and desire to secure by Letters Patent.—

1. A toy shooter consisting of a plate in the form of a pistol having a recess therein containing a hammer tensioning spring, a hammer, means for holding an elastic ball by frictional engagement on said plate, and a trigger for controlling said hammer.

2. A toy shooter consisting of a flat body forming a hand grip approximately in the form of a pistol grip and having a recess which provides fixed jaws adapted to hold therebetween a ball pressed thereinto and held by frictional engagement, and a spring

returned hammer arranged to strike said ball.

3. In a toy shooter, a disk of metal having the outlines of a pistol grip with a recess therein which forms a pair of jaws and takes the place of the usual pistol barrel, a hammer arranged to strike a ball held in said jaws, means for actuating the hammer, and a ball adapted to be held in said jaws.

4. In a toy pistol, a pistol grip having a recess therein forming a pair of jaws, a hammer formed of a sheet of metal straddling said grip and arranged to strike a ball held in said jaws, and means for actuating said hammer.

In testimony whereof I have hereunto signed my name.

NELS G. NELSON.
